UNITED STATES PATENT OFFICE.

JASPER FRED KOBLER, OF NIAGARA FALLS, NEW YORK.

CAPSULE-FILLING MACHINE.

No. 828,611.

Specification of Letters Patent.

Patented Aug. 14, 1906.

Application filed February 20, 1905. Serial No. 246,370.

To all whom it may concern:

Be it known that I, JASPER FRED KOBLER, a citizen of the United States, residing at Niagara Falls, in the county of Niagara and State 5 of New York, have invented a new and useful Capsule-Filling Machine, of which the following is a specification.

This invention relates more particularly to means for introducing material into capsules. 10 The principal object is to provide novel mechanism of a simple nature whereby material can be equally and properly divided into doses or portions and placed in capsules or like holders, said mechanism being very 15 convenient to use and eliminating the tedious operation of filling capsules by hand with its variable results.

An embodiment of the invention that is at present considered the preferable one is illustrated in the accompanying drawings, where- 20 in—

Figure 1 is a side elevation of the apparatus. Fig. 2 is a vertical cross-sectional view therethrough on the line A A of Fig. 1. Fig. 25 3 is a vertical sectional view at right angles to Fig. 2 and on the line B B of Fig. 4. Fig. 4 is an end elevation of the machine. Fig. 5 is a view similar to Fig. 3, but showing the press opened and a cake of material formed there- 30 in. Fig. 6 is a horizontal sectional view on the lines C C of Fig. 5. Fig. 7 illustrates the evener in side and edge elevation.

Similar reference characters designate corresponding parts in all the figures of the drawings. 35

In the embodiment illustrated a base comprising sections 1 are provided with upstanding parallel side walls 2, having upper extensions at their upper corners in the form of 40 ears 3. A bottom 4, located between the lower portions of the side walls 2, is provided with upwardly-extending portions disposed between the sides. These various elements are secured together by bolts 5 passing 45 through the side walls 2 and the bottom and end member. As a result a chamber D is formed, which, as shown in Fig. 6, is oblong.

A pressing-plunger 6 is movable in the chamber D and has an upstanding stem 7, 50 which is screw-threaded. This stem has a threaded engagement with the flanged hub 8 of a hand-wheel, said hand-wheel comprising spokes 9 and a rim 10. The hub 8 is journaled in a yoke comprising a collar 13, having 55 opposite outwardly-extending arms 14, one of said arms being pivoted to one of the sets

of ears 3 by a bolt 15 and the other arm being detachably secured to the other set of ears 3 by a loose pin-bolt 16. The hub 8 is maintained in place in the collar 13 by a retaining- 60 ring 11, that engages over the flange of said hub and is held to the collar by screws or other fasteners 12.

The bottom 4 is provided with a series of transverse grooves in which are seated a plurality of tubes 22, said tubes projecting through and beyond the side walls 2. One series of projecting ends constitute capsule-holding nipples and are spaced a sufficient distance apart to allow of a capsule, as 20, 70 being placed upon each. The other projecting portions of the tubes that extend from the opposite side of the casing constitute inlet ends, the terminals being preferably cut away, as shown in Figs. 2 and 4. The portions of the tubes that are located within the chamber D have their upper halves cut away, so that the bores of said tubes have communication with the interior of the chamber, and the capsule-holding nipples thus have 80 discharge outlet-openings communicating with said chamber. The open-sided portions of the tubes located within the chamber constitute pockets or channels for the reception of the material. The bottom or under side 85 of the pressing-plunger 6 has corresponding pockets or channels 29, which coöperate with those formed by the tubes, so that when the plunger is in place within the chamber the bottom thereof will complete the channels 90 and form completed bores equal in diameter to the bores of the tubes.

In connection with the above-described mechanism means are employed for forming a preliminary cake of the material to be divided within the chamber D. In the present embodiment this means consists of a slide 18, that comprises a partition or false bottom which removably passes through a slot 17 in one end of the chamber and is movable over 100 the tops of the pockets or channels. A press-block 23 is arranged to fit within the chamber D and is employed when the slide 18 is in place therein. A leveling-gage 25 is also employed, the same being formed of slidably-associated sections which are adapted to be held in adjusted relation by a thumb-nut 27. One of the sections is arranged to fit between the side walls 2, while the other is provided with outstanding lugs 28, that ride upon the 105 upper edges of said side walls.

Briefly described, the structure is em-

ployed as follows: The capsules to be filled are placed upon the discharge-nipples and the slide 18 is arranged within the chamber over the channels or pockets. The material to be placed in the capsules is then introduced into the chamber upon the slide 18. This material is then leveled and smoothed by the gage 25, the amount of the material being varied to suit the different requirements and the depth at which the gage acts being adjusted by sliding the two sections upon each other and securing them, as will be understood by reference to Fig. 7. After the material has been properly smoothed the press-block 23 is placed thereupon and a preliminary compacting of the material is made thereby. A cake is thus formed, which is shown in Fig. 5 and is designated 24. The slide 18 and press-block 23 are then removed and the yoke, with its pressing-plunger, is swung over the chamber, said yoke being secured. It will thus be apparent that if the hand-wheel 10 is rotated in the proper direction the pressing-plunger 6 will be forced downward and the cake divided into sections or doses which are cylindrical in form and of a proper diameter to pass freely through the discharge-nipples. An expelling-plunger 21 is then employed which is passed into the inlet ends of the tubes 22 and across the chamber, thereby expelling the material through the nipples into the capsules and in turn expelling the capsules from the nipples.

It will thus be seen that an exceedingly simple structure is provided whereby material may be equally divided with ease and expedition and easily placed in capsules or other holders, thereby eliminating the tedious manual filling operation now ordinarily employed.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

Having thus fully described my invention, what I claim as new, and desire to secure by Letters Patent, is—

1. In a machine of the character described, the combination with a chamber having an outlet, of expelling means operating toward and from the outlet, and material-pressing means movable transversely of the path of movement of the expelling means.

2. In a machine of the character described, the combination with a chamber having a plurality of discharge outlet-openings in one side, of expelling means operating across the bottom of the chamber, and pressing means movable in said chamber toward the bottom.

3. In a machine of the character described, the combination with a chamber having a wall provided with a capsule-holding nipple projecting from one side and having a discharge outlet-opening therethrough communicating with the interior of the chamber, of means operating across the chamber for expelling material through the nipple and into a capsule placed thereon. 70

4. In a machine of the character described, the combination with a chamber having a wall provided with a plurality of capsule-holding nipples projecting from one side and having discharge-openings therethrough communicating with the interior of the chamber, 75 said nipples being spaced apart to permit the placing of a capsule on each, of means operating through the opposite side of the chamber and across said chamber for expelling the material placed in said chamber through the nipples and into capsules placed thereon. 80

5. In a machine of the character described, the combination with a chamber having a wall provided with a plurality of outwardly-projecting capsule-holding nipples, said nipples having discharge-openings therethrough communicating with the interior of the chamber, and said chamber having openings in its opposite sides in alinement with the nipples, and a plunger that is movable through the 90 openings to expel the material from the chamber through the nipples. 95

6. In a machine of the character described, the combination with a chamber having a wall provided with a capsule-holding nipple 100 projecting from one side of the same, said nipple having a discharge-opening communicating with the interior of the chamber, of means operating across the chamber for expelling the material therein through the nipple and into a capsule placed thereon, and material-pressing means operating in the chamber transversely of the nipple. 105

7. In a machine of the character described, the combination of a chamber having a wall 110 provided with a plurality of outwardly-projecting capsule-holding nipples, said nipples having discharge-openings communicating with the interior of the chamber, said chamber also having openings in its opposite wall 115 in alinement with the nipples, a plunger that is movable through the openings and into the chamber to expel the material therein through the nipples, and a presser-plunger operating in the chamber transversely of the 120 nipples.

8. In a machine of the character described, the combination with a chamber, of tubes extending across the chamber and having open sides located therein, said tubes projecting 125 from one side of the chamber, forming discharge-nipples, and means for expelling the material through the tubes and through said nipples.

9. In a machine of the character described, 130

the combination with a chamber having side walls, of a plurality of tubes extending across the lower portion of the chamber and having open sides located therein, said tubes projecting beyond the sides of the chamber, forming discharge-nipples and inlet ends, and an expelling-plunger that is movable through the inlet ends.

10. In a machine of the character described, the combination with a chamber having a discharge-opening in one side, and a bottom provided with a channel that is alined with the opening, of means for pressing material into the channel, and means for expelling the material from the channel through the discharge-opening.

11. In a machine of the character described, the combination with a chamber having a discharge-nipple at one side, said nipple being provided with a discharge-bore, of means within the chamber for forming the material placed therein into the shape of the nipple-bore, and means for expelling the material, when so shaped, through the bore.

12. In a machine of the character described, the combination with a chamber having a discharge-opening in one side, and a bottom provided with a channel alined with the opening, of a presser-plunger operating in the chamber and having a channel that coacts with the bottom chamber to form a bore alined with the opening, and a plunger for expelling the material in such bore through the opening.

13. In a machine of the character described, the combination with a chamber having side walls, and a bottom, of tubes extending through the side walls and across the bottom, said tubes having open sides within the chamber and furthermore having their ends projecting beyond one of the side walls and forming capsule-holding nipples, a presser-plunger operating in the chamber over the tubes and having channels that coact with the open sides of the tubes, and means operating in the tubes for expelling the material therein.

14. In a machine of the character described, the combination with a chamber having side walls and openings therein, of means for expelling the material through said openings, a presser-plunger, and means for forcing said presser-plunger downwardly into the chamber.

15. In a machine of the character described, the combination with a chamber having side walls and openings therein, of means for expelling material through said openings, a yoke extending over the chamber, a presser-plunger, and screw-operating means connecting the yoke and plunger.

16. In a machine of the character described, the combination with a chamber having pockets in its bottom, of a partition movable over said pockets, and a presser de-

vice movable in said chamber over the partition.

17. In a machine of the character described, the combination with a chamber having pockets or channels in its bottom and discharge-openings alined therewith, of a movable partition slidably mounted in the chamber over the pockets, a presser device movable in said chamber over the partition, and means for expelling the material from the pockets.

18. In a machine of the character described, the combination with a chamber having pockets or channels in its bottom, of a removable partition slidably mounted in the chamber over the pockets, a presser-plunger operating in the chamber and having pockets or channels in its under side, and means for expelling the material from said pockets or channels.

19. In a machine of the character described, the combination with a channel having spaced upright side walls, said walls having a plurality of openings for the reception of a plurality of tubes, of a bottom for the chamber having upper extensions at its ends, and tubes extending within the chamber and having portions therein cut away to form outlets from the bottom of the chamber.

20. In a machine of the character described, the combination with a chamber having channels in its bottom, of a pressing device movable in the chamber, and having channels in its under side that coact with the channels of the chamber-bottom to form separate bores.

21. In a machine of the character described, the combination with a chamber having walls provided with upright extensions, of a yoke pivotally mounted on the extensions and comprising a collar having outwardly-extending arms pivoted to the extensions, a plunger operating in the chamber and having a threaded stem passing through the collar, and a hub portion journaled in the collar of the yoke and having a threaded engagement with the stem of the plunger.

22. In a machine of the character described, the combination with a chamber, of tubes located side by side and projecting beyond the chamber, forming nipples, said nipples being spaced a sufficient distance apart to allow of a capsule being placed upon each, and an ejecting-plunger that slidably operates in the tubes.

23. In a machine of the character described, the combination with a chamber having a bottom provided with a plurality of grooved seats, of tubes located in the seats, a pressing-plunger movable in the chamber, a detachable press-block also movable in the chamber, and a sliding bottom for the chamber movable over the tubes.

24. In a machine of the character described, the combination with a chamber, of

a false bottom removable through one side of the chamber, a press-block operating in the chamber over the false bottom, and a pressing-plunger operating in the chamber when the false bottom and press-block are removed.

25. In a machine of the character described, the combination with holding means for a plurality of capsules, of means for forming a cake of material, means for dividing said cake into sections of a size to enter the

capsules, and means for delivering the sections into capsules associated with the holding means.

In testimony whereof I have signed my name to this specification in the presence of 15 two subscribing witnesses.

JASPER FRED KOBLER.
